AIRPLANE CONTROL SURFACES

Temple N. Joyce, Arnold, Md., assignor to Zap Development Corporation, Baltimore, Md., a corporation of Delaware

Application July 20, 1938, Serial No. 220,368

3 Claims. (Cl. 244—42)

This invention relates to airplanes and more particularly to control surfaces for airplanes.

The present invention is generally similar to that covered in my co-pending application 220,359 filed concurrently herewith but includes additional important features.

An object of the present invention is to provide a flap and aileron construction in which the flap can extend substantially the full length of the airplane wing.

Another object of my invention is to provide an airplane wing that will have proper lateral control when the plane is flying at either high or low speeds.

Yet a further object of my invention is the provision of a flap and aileron combination that will form the trailing edge of the wing.

Yet another object of my invention is the provision of spoiler, flap and aileron surfaces so associated that the aileron cannot be operated as long as the flap is in its inoperative position.

To accomplish the above and additional objects, this invention comprehends the employment of a wing having spoiler, flap and aileron surfaces that are so associated that when the airplane is flying at high speeds, the flap and aileron are in their inoperative positions. Due to the manner in which these surfaces are connected, it is not possible to actuate the aileron as long as the flap is in its inoperative position. The spoilers, however, are free to be operated at high speeds, thereby giving the necessary lateral control for the airplane.

When the airplane is flying at low speed and the flap is lowered by the pilot, means are provided whereby the aileron can be operated.

In order to readily comprehend my invention, attention is directed to the accompanying drawing which illustrates the preferred embodiment of my inventive concept, it being understood, however, that numerous changes may be made by those skilled in the art without exceeding the scope of the invention as described by the annexed claims.

In the drawing in which like numerals designate similar parts:

Figure 1 is a view in side elevation, partly in section, of an airplane wing depicting my invention.

Figure 2 is a fragmental sectional view of the trailing edge of the wing shown in Figure 1 illustrating the flap in its lowered position and the aileron free to be actuated.

Figure 3 is a view taken along line 3—3 of Figure 1 looking in the direction of the arrows.

Referring particularly to Figure 1, there is shown an airplane wing 1 having a front spar 2 and a rear spar 3. The wing is provided with a flap 4 and an aileron 5 which, it will be noted, form the trailing edge of the wing 1.

A spoiler 6 which is hinged to the upper leading edge of the wing 1 as shown at 7 is adapted to fit within a well 8 when the spoiler is in its inoperative position. Of course, it is to be understood that the spoiler can be disposed at any location on the upper area of the wing, or a plurality of spoilers can be used.

To move the spoiler about its pivot 7, it can be seen that a bell crank 9 is pivotally mounted at 10 to a support 11 secured to the front spar 2. A link 12 is attached at one end to the bell crank and at its opposite end to the undersurface of the spoiler 6. The other arm of the bell crank 9 is attached to an operating cable 13 by a pivotal connection 14. A coil spring 15, one end of which is fixed to the nose of the wing and the other end being attached to the connection 14, is adapted to hold normally the spoiler 6 within the well 8 as shown in Figure 1. As will later become more readily apparent, the spoiler 6 is adapted to be moved into the airflow over the wing when the plane is flying at high speed to provide the necessary lateral control.

The operating cable 13 may be associated in any desired manner with the pilot's controls (not shown).

As shown in Figure 2, the flap 4 is provided with upstanding supports 16 in which is journaled a stub shaft 17. A link 18 is attached to the shaft 17 and the outer end is fixed by pivoting to a tube 19 extending through the leading edge of the aileron 5.

It can be noted that a pair of the braces for the interior of the wing are provided with elongated slots 20. A shaft 21 that extends through apertures in the supports 16 of the flap 4 carries rollers 22 that ride in the slots 20.

An operating link 23 is attached to the shaft 21 and extends through an aperture 24 in the rear spar 3. The opposite end of the link 23 is pivotally attached as shown at 25 to operating arms 26 that are in turn secured to a torque tube 27 journaled in the wing's interior bracing members.

A control rod 28 that extends to a position convenient for the pilot is pivotally attached to a sleeve 29 secured to the torque tube 27.

It will be readily apparent to those skilled in the art that when the flap 4 is in the position shown in Figure 1 it is not possible to lower the

aileron 5. However, the spoilers 6 are free to be operated and provide for the necessary lateral control.

- When it is desired to lower the flap 4, it will be appreciated that by actuating the control rod 28, the torque tube 27 will be rotated and the arms 26 will move through an arc forcing the link 23 rearwardly and causing the rollers 22 to ride in the slot 26 moving the flap to the position shown in Figure 2. While I have shown the use of a flap which lies substantially directly beneath the trailing edge of the aileron when it is lowered, it is manifest that other types of flaps may be employed.
- When the flap is in its lowered position as shown in Figure 2, the aileron 5 is free to be operated by the pilot. For example, in Figure 3, I have shown an operating rod 30 attached to the tube 19 as shown at 31 for actuating the aileron 5.

It is believed readily apparent from the foregoing that there is provided a system of lateral control for airplanes that will be highly effective under all conditions of flight. By having the aileron 5 and the flap 4 connected in the manner shown, the aileron cannot be moved to its operative position as long as the flap is in its inoperative position.

The spoilers 6, however, are free to be operated when the flap and aileron are in their inoperative positions. By employing the spoiler surfaces 6 to afford lateral control at high speeds, parasitic drag is materially reduced.

On the other hand, when the plane is flying at a low speed and the flap is lowered, the aileron 5 can then be operated by the pilot. The aileron is highly effective at low speeds inasmuch as it is stimulated by the flow of air over the top surface of the wing by the flap 4.

While I have shown the preferred embodiment

40

of my invention, it is, of course, to be understood that I am not limited to the precise details herein set forth but that the scope of my invention is to be determined by the annexed claims.

I claim:

1. In an airplane, a wing, a flap adapted to be raised and lowered, an aileron adapted to be actuated downwardly, said flap and aileron forming the trailing edge of the wing, a link pivotally mounted at one end to the flap and at the opposite end to the aileron, a second link pivotally attached to the flap at a point forward of the pivot point of the other link to the flap, means associated with said second-mentioned link to lower the flap, said flap when raised lying adjacent the aileron so as to prevent downward actuation of the aileron, and means to actuate the aileron when the flap is lowered.

2. In an airplane, a wing, a flap, an aileron, said flap and aileron forming the trailing edge of the wing, a rotatable shaft fixed to the leading portion of the aileron for swinging the aileron upwardly and downwardly, means for slidably and pivotally supporting the leading portion of the flap on the wing, and a link pivoted between said shaft and the flap for guiding the flap for downward swinging thereof, said flap when raised lying adjacent the aileron so as to prevent downward swing of the aileron.

3. In an airplane, a wing, a flap adapted to be raised and lowered, an aileron adapted to be actuated downwardly, a link interconnecting said flap and aileron for guiding downward swing of the flap independently of movement of the aileron, said link guiding the flap when raised to a position adjacent the aileron so as to prevent downward actuation of the aileron, and means for actuating the aileron downwardly when the flap has been lowered.

TEMPLE N. JOYCE.
